KNOCKDOWN BOX OR CRATE

Filed Oct. 25, 1945

UNITED STATES PATENT OFFICE

2,460,104

KNOCKDOWN BOX OR CRATE

Leon R. Rapp, Carpenterville, N. J.

Application October 25, 1945, Serial No. 624,411

5 Claims. (Cl. 217—12)

1

This invention relates to an improvement in knockdown boxes or crates, and more particularly to that type of container which may be assembled without employing fastening means, such as nails or screws, and the like.

The invention consists of two angle-iron end frames in which are mounted the bottom, sides and ends of the container, and which latter are so positioned within the frames and held together in the frames without fastening means to provide a rigid and sturdy container.

The invention consists of certain novel features of construction and combinations of parts which will be hereinafter described and pointed out in the claims.

In the accompanying drawing:

Figure 1 is a perspective view of an assembled box or crate;

Figure 2 is a horizontal vertical sectional view, and illustrating the manner of assembling the end members for securing the bottom and sides to the end frames;

Figure 3 is a perspective view of one of the metal end frames;

Figure 4 is a detail view in elevation of one of the side members;

Figure 5 is a detail sectional view taken on line 5—5 of Figure 2; and

Figure 6 is a detail view in perspective of a bottom member.

This invention is primarily adapted to the construction of boxes or crates for holding bottles containing beverages, but may be employed for other purposes, and as shown in the drawing is of rectangular shape, although it will be recognized that other shaped containers could be made.

The box or crate has two rectangular metal end frames 10, 10 L-shaped in cross-section, consisting of an inwardly extending flange portion 11, and an outwardly extending flange portion 12. The angle iron frames 10 are preferably arranged in a one-piece structure by having the ends of the flange 12 welded together, and the flanges 11 so welded together at the corners of the frame, so that a rigid construction is provided. The flange 12 is provided at its free end edge with an inwardly turned rib or lip 13.

The bottom 14 of the box or crate is preferably made up of a plurality of wood slats 15, Figure 6, although it may be formed of a single piece of wood. The slats are provided on their under surface and adjacent each end with grooves or slots 16, for the reception of the lips or ribs 13 of the flange 12, Figure 2, and the ends of the bottom slats engaging the flange 11. Mounted upon

the bottom 14 are side members 18, which are provided with grooves or slits 19 on the outer surface and near the ends and across the upper edge thereof for the reception of the ribs 13. The ends of the side member 18 engaging the flanges 11.

The bottom 14 and side members 18 are assembled in the angle iron frames 10, by causing the ends thereof to engage the flange portions 11 and bearing against the flange portions 12 and having the ribs 13 entering the grooves of the respective members. The end members 20 are of a size to have a snug fit between the sides 18, and between the bottom 14 and one of the flanges 12 of the frames 10. The end members are inserted between the side members 18 and inclined sufficiently to cause the upper edges or ends thereof to be first inserted into the frame members 10, between the flange 11 and rib 13 of the flange 12, and then forcing the lower portions of the end members into engagement with the flange 11. This movement of the end members into the frame members causes the sides 18 and bottom 14 to be securely connected to the end frames 10 and the frictional engagement between these members insures them against removal or the collapsing of the box during ordinary usage.

However, if it is desired to collapse the box the end members 20 can be forced inwardly at their lower ends until they can be disengaged from the end frames and ribs 13, whereupon the end members may be removed and the sides and bottom disengaged from the end frames.

The flange portions 11 may be provided with holes 22 for the reception of nails or screws for securing the ends to the end frames, but such means of fastening would ordinarily be employed due to shrinkage, warpage or some injury to the end members, as under usual conditions of usage the box or crate will have all of the necessary rigidity and security when assembled as above set forth.

With the end frames 10 made of a single-piece unit and the flange portion 12 provided with ribs 45 or lips 13 along each of the four edges the bottom and sides are interlocked with the end frames, and insuring the box or crate remaining in assembled relation after the end members 20 are inserted into the frame members and between 50 the sides and bottom.

What I claim is:

1. A box or crate comprising bottom, side and end walls, and one-piece metal end frames, ribs extending inwardly from the walls of said end frames, said bottom and sides being provided with

slots along one surface and adjacent the ends thereof, said bottom and sides having the ends thereof received in said end frames and said ribs of said end frames received in said slots for connecting the bottom and sides to said end frames, said end walls disposed between said sides and upon said bottom and forced into said end frames in rear of said rib for securing said bottom and side walls to said end frames.

2. A box or crate comprising bottom, side and end walls, and rectangular metal end frames, ribs extending inwardly from the walls of said frames, said bottom and sides being provided with slots along one surface and adjacent the ends thereof, said bottom and sides having the ends of said received in said end frames and said ribs of said end frames received in said slots for connecting the bottom and sides to said end frames, said end walls disposed between said sides, each of said end walls having an end thereof inserted in a respective end frame in rear of said rib of said end frames, and said end walls then forced into its said respective end frame for securing the side and bottom walls to said end frames.

3. A box or crate comprising bottom, side and end walls, and one piece rectangular metal end frames, said end frames consisting of inwardly and outwardly extending flange portions, ribs on said outwardly extending flange portion extending inwardly therefrom and substantially parallel to said inwardly extending portions, said bottom and sides having slots formed on one surface near the ends thereof, said bottom and sides having the ends thereof received in said end frames and engaging the inwardly extending portions thereof and said ribs of said outwardly extending portions entering said slots of said bottom and side walls, each of said end walls disposed between said side walls and on said bottom wall and inserted in its respective end frame with an end thereof disposed between one of said ribs and one of said inwardly extending portions of said end frames.

4. A knockdown box or crate comprising bottom, side and end walls, and two endless metal end frames each consisting of unitary outwardly

extending flanges and inwardly extending flanges, a rib on said outwardly extending flange extending inwardly therefrom and substantially parallel to and in spaced relation to said inwardly extending flange, said bottom and sides having the ends thereof received in said end frames, said bottom and sides being provided with slots for the reception of said rib of said end frames, for connecting the end frames together, said end walls being disposed between said sides and on said bottom, each of said end walls inserted in and housed in a respective end frame with an end thereof disposed between said rib and inwardly extending flange of said end frames for securing the end frames, bottom and sides together.

5. A box or crate comprising bottom, side and end walls, and two endless angle iron metal end frames, each consisting of outwardly and inwardly extending flanges, a rib on said outwardly extending flange extending inwardly therefrom and substantially parallel to and in spaced relation to said inwardly extending flange, said bottom and sides having the ends thereof received in said end frames, said bottom having slots on one surface thereof and said sides having slots on one surface thereof and on the edges thereof for the reception of said rib of said end frames for connecting the end frames together, said end walls being disposed between said sides and on said bottom and inserted within said end frames, said end walls each having an end thereof disposed between said rib and said inwardly extending flange of said end frames for securing said bottom and sides to said end frames.
